UNITED STATES PATENT OFFICE.

PAUL MOHRMANN, OF CHICAGO, ILLINOIS, ASSIGNOR TO FRIEDELEY-VOSHARDT COMPANY, OF CHICAGO, ILLINOIS, A CORPORATION OF ILLINOIS.

DESIGN FOR A PLATE FOR DROP-LIGHT FIXTURES.

45,764.

Specification for Design.

Patented May 12, 1914.

Application filed February 27, 1914. Serial No. 821,579. Term of patent 3½ years.

To all whom it may concern:

Be it known that I, PAUL MOHRMANN, a citizen of the United States, residing at Chicago, in the county of Cook and State of Illinois, have invented a new, original, and ornamental Design for a Plate for a Drop-Light Fixture, of which the following is a specification, reference being had to the accompanying drawings, forming a part thereof.

In the drawings: Figure 1 is a bottom plan view of a plate embodying this design.

Fig. 2 is a section taken as indicated at line 2—2 on Fig. 1.

I claim:

The ornamental design for a plate for drop-light fixtures, as shown.

In testimony whereof I have hereunto set my hand at Chicago, Illinois, this 24th day of February, 1914.

PAUL MOHRMANN.
